(57) **CLAIM**

We claim the ornamental design for a test switch, as shown and described.

DESCRIPTION

FIG. 1 is a front and right side perspective view of a test switch of the present invention;

FIG. 2 is a front elevational view of the FIG. 1 test switch;

FIG. 3 is a rear elevational view of the FIG. 1 test switch;

FIG. 4 is a left side elevational view of the FIG. 1 test switch;

FIG. 5 is a right side elevational view of the FIG. 1 test switch;

FIG. 6 is a top plan view of the FIG. 1 test switch; and,

FIG. 7 is a bottom plan view of the FIG. 1 test switch.
